UNITED STATES PATENT OFFICE.

JOHN S. MONAGHAN, OF ROCHESTER, NEW YORK, ASSIGNOR TO GERMAN-AMERICAN
BUTTON COMPANY, OF ROCHESTER, NEW YORK, A CORPORATION OF NEW YORK.

DESIGN FOR A BUTTON.

50,846.

Specification for Design.

Patented May 29, 1917.

Application filed April 4, 1917. Serial No. 159,788. Term of patent 3½ years.

To all whom it may concern:

Be it known that I, JOHN S. MONAGHAN, a citizen of the United States, and a resident of Rochester, Monroe county, State of New York, have invented a new, original, and ornamental Design for Buttons, of which the following is a specification.

My design is represented in the accompanying drawing, in which:

Figure 1 is a plan view showing my new design.

Fig. 2 is a side elevation looking in the direction of the arrow 2 of Fig. 1.

Fig. 3 is a side elevation looking in the direction of the arrow 3 in Fig. 1.

The button has a flat upper surface gradually receding from the center toward the edge. Three similarly shaped arms project from the center at an angle of 120° from each other. The outer edges of each are

convex and extend substantially through an angle of 60°. The arms are connected to one another by concave surfaces each of which extends across an angle of substantially 60° from the center of the button. Just above each of the concave surfaces steps are formed, the upright sides of which are substantially crescent shaped.

I claim—

The ornamental design for a button substantially as shown and described.

In witness whereof I have hereunto set my hand at the borough of Manhattan, city and State of New York this seventeenth day of March 1917.

JOHN S. MONAGHAN.

In presence of—

ISABEL R. RICHARDS,
ZITA M. GRAHAM.
